United States Patent Office

Des. 181,593

Patented Dec. 3, 1957

181,593

AUTOMOBILE

Clare M. MacKichan, Farmington, and Joseph R. Schemansky, Birmingham, Mich., assignors to General Motors Corporation, Detroit, Mich., a corporation of Delaware

Application August 25, 1954, Serial No. 32,016

Term of patent 7 years

(Cl. D14—6)

Fig. 1 is a front view of an automobile showing our new design;

Fig. 2 is a fragmentary top plan view of the front portion of the automobile; and

Fig. 3 is a vertical transverse section through the front portion of the automobile along the line 3—3 of Fig. 1.

Figure 4 is a perspective view of the automobile.

The dominant features of our design reside in the full line portions of the drawings.

We claim:

The ornamental design for an automobile, substantially as shown and described.
